BOTTLE CARRIER

Elmer H. Lupton, Ilchester, Md.

Application September 1, 1938, Serial No. 228,042

6 Claims. (Cl. 229—27)

This invention relates to improvements in bottle carriers. The carrier of my invention comprises a strip of paper board or similar flexible material divided by crease lines into a bottom panel and two side panels of equal length, the end portions of the side panels having hand holes and interlocking means and constituting the handle portion of the carrier. The bottom panel is of a suitable size to support two rows of bottles side by side, and to space the bottles apart and hold them in position on the bottom, I provide on the blank a spacing strip having two rows of openings to receive the bottles. This spacing strip is supported above the bottom by hinged flaps connecting its ends with the ends of the bottom panel. In setting up the carrier, the side panels are turned upwardly and they engage the sides of the spacing strip, and interlocking connections are provided between the side panels and the spacing strip or its supporting flaps so that the latter will be maintained in their upright positions. The handle portions of the side panels are then locked together. A large opening is made in each side panel through which the bottles may be inserted or removed. Tongues cut out of the side panels, depend from the handle portion and extend between the rows of bottles and assist in maintaining them in upright positions.

In the accompanying drawings,

Fig. 1 is a plan view of the blank from which the carrier shown in Figs. 2-4 is formed;

Fig. 1^a is an outline view showing the spacing strip of the blank connected to both supporting flaps;

Fig. 2 is a perspective view of the carrier with rows of bottles therein;

Fig. 3 is a transverse section taken centrally through Fig. 2;

Fig. 4 is a horizontal section on the line 4—4 of Fig. 3;

Fig. 5 is a plan view of a portion of a blank for forming a carrier as in the preceding figures, but showing an alternative locking means for preventing endwise movement of the spacing member, and,

Fig. 6 is a detail view illustrating the manner in which the locking means of Fig. 5 is applied.

Referring to Fig. 1 of the drawings, A represents a blank of cardboard, or analogous flexible material, comprising a strip *a* scored transversely as shown at 1 and 2, dividing the strip into a central panel 4 which constitutes the bottom of the carrier and two panels 5 and 6 which form the sides and handle portions of the carrier.

Connected to the ends of the bottom panel 4 are flaps 7 and 8 which are foldable upwardly with respect to said panel along crease lines 9 which are in line with the edges of the strip *a*. The flap 8 is integral with a strip *b* which is foldable with respect to said flap along the crease line 10. The strip *b* has two rows of circular openings 11 and 12, each opening of the proper diameter to permit the body of a bottle to fit freely within it. In the completed carrier, the end portion 13 of the strip *b* is glued or otherwise secured to the flap 7 and when the flaps 7 and 8 are in upright position, they support the strip *b* above and parallel with the bottom panel 4, as shown in outline in Fig. 1^a and also shown in Figs. 2 and 3. The strip *b* and its supporting flaps constitute means for spacing the bottles apart and holding them in position upon the bottom panel. As the flaps 7 and 8 are hinged to the ends of the bottom panel and also to the spacing strip *b*, it is necessary to interlock these members with the side panels 5 and 6 when the carrier is set up, in order to prevent endwise movement of the strip with respect to the bottom panel, and for this purpose pairs of tabs 14 and 15 are provided on the strip *a* at its opposite edges, adjacent the flaps 7 and 8, respectively, and when the side panels 5 and 6 are raised as in Figs. 2 and 3, these tabs are inserted in the space between the strip *b* and the bottom panel 4, adjacent the flaps and between the flaps and the end bottles in the rows, as shown in Figs. 3 and 4.

Each of the panels 5 and 6 of the blank has short crease lines 16 and 17 extending inwardly from its side edges, these lines being spaced from the lines which define the bottom panel by a distance equal to approximately the height of the bottles to be carried, and from the inner ends of these crease lines a downwardly curving cut 18 is made in each side panel of the blank, thus forming a large opening 19 in each side of the carrier through which the bottles *c* may be inserted into the openings in the spacing member *b* and onto the bottom panel 4, and by the same cuts correspondingly large tongues 20 are formed, which tongues, as shown in Figs. 2 and 3, extend downwardly between the rows of bottles, when the carrier is set up and filled, serving as separators between the rows of bottles and helping to maintain them in upright positions so that the bases of the bottles rest flatly against the bottom panel 4.

The handle portion of the side 6 comprises the part 6^a of the blank between the crease lines 16—17 and a crease line 21, beyond which is a

part 6^b which folds along the crease line 21 against the part 6^a and is glued to the latter, forming a handle portion of double thickness. Oblong openings 22^a in the parts 6^a and 6^b of the blank register when these parts are glued together and form a hand opening 22 in the handle portion of the completed carrier. Similarly the extension 5^a of the side 5 of the blank between its crease lines 16-17 and the crease line 23, and a part 5^b which folds against the part 5^a and is glued to it, form a double thick handle portion for the side 5 of the carrier. Tongues 24^a punched out of the parts 5^a and 5^b register with one another when these parts are folded and glued together, and these form a tongue 24 of double thickness adapted to extend through the opening 22 in the handle portion of the side 6 of the carrier, as shown in Figs. 2 and 3. The head on this tongue is wider than the length of the opening 22, so that when the tongue is pushed through the opening, the handle portions are locked together. If desired, the tongue and opening in the handle portions may be punched out after the parts composing these portions have been folded and glued together.

To set up the carrier shown in Figs. 2 and 3, the sides 5 and 6 are folded upwardly, the tabs 14 and 15 on their edges at the same time being inserted between the spacing strip b and the bottom panel 4, alongside the end flaps 7 and 8, respectively, and the handle portions are locked together by the locking tongue 24. The bottles can then be inserted through the openings 19 in the sides, the separating tongues 20 being pushed inwardly by this operation so that they occupy a position between the rows of bottles. The tabs 14 and 15 on the sides then lie between the flaps 7 and 8 and the end bottles in the rows. When the carrier is filled the upper portions of the bottles are exposed to view, as is desirable. The individual bottles can be removed by simply lifting them through the side openings of the carrier.

Instead of providing the tabs 14 and 15 on the side members of the carrier to interlock with the end flaps 7 and 8 of the spacing member, these flaps may be extended as shown in Figs. 5 and 6 so that their ends will abut against the edges of the sides when the latter are in upright position. Thus, as shown in Fig. 5, the end flap 7^a is extended beyond the crease lines 1 and 2 which define the width of the bottom panel 4 and the end flap 8^a is similarly extended and made longer than the width of the bottom panel 4 and the spacing strip b. Fig. 6 is a detail view showing the sides 5 and 6 in cross-section in their vertical positions with the extended ends of the flaps 7^a and 8^a engaging the edges of the side members, from which it will be evident that when the carrier is set up there can be no longitudinal movement of the spacing strip b which is supported by the flaps. Figs. 5 and 6 are intended to merely show the alternative locking means between the sides and the spacing strip. It will be understood, without illustration, that the other features of the carrier are the same as in the previously described figures.

What I claim is:

1. A bottle carrier comprising an elongated strip of flexible material creased transversely forming a bottom panel adapted to support two rows of bottles extending side by side transversely of the strip and two side panels adapted to fold upwardly along said crease lines, the end portions of the side panels having registering

openings and constituting the handle portion of the carrier, means for spacing the bottles apart and for holding them in position on the bottom panel comprising a spacing strip of approximately the same dimensions as the bottom panel and having openings through which the lower parts of the bottles may extend and flaps hinged to the ends of the bottom panel and the spacing strip and adapted to support the latter strip above the bottom panel, and interlocking devices between said spacing means and said side panels for preventing endwise movement of the spacing means when the side panels are in their upright positions.

2. A bottle carrier comprising an elongated strip of flexible material creased transversely forming a bottom panel adapted to support two rows of bottles extending side by side transversely of the strip and two side panels adapted to fold upwardly along said crease lines, the end portions of the side panels having registering openings and constituting the handle portion of the carrier, means for spacing the bottles apart and for holding them in position on the bottom panel comprising a spacing strip of approximately the same dimensions as the bottom panel and having openings through which the lower parts of the bottles may extend and flaps hinged to the ends of the bottom panel and the spacing strip and adapted to support the latter strip above the bottom panel, the side panels having tabs at their edges adjacent the bottom panel adapted to enter between the spacing strip and bottom panel and engage the inner sides of the flaps to prevent endwise movement of the spacing means when the side panels are in their upright positions.

3. A bottle carrier comprising an elongated strip of flexible material creased transversely forming a bottom panel adapted to support two rows of bottles extending side by side transversely of the strip and two side panels adapted to fold upwardly along said crease lines, the end portions of the side panels having registering openings and constituting the handle portion of the carrier, means for spacing the bottles apart and for holding them in position on the bottom panel comprising a spacing strip of approximately the same dimensions as the bottom panel and having openings through which the lower parts of the bottles may extend and flaps hinged to the ends of the bottom panel and the spacing strip and adapted to support the latter strip above the bottom panel, the ends of the flaps projecting beyond the side edges of the spacing strip and adapted to bear against the side edges of the side panels and prevent endwise movement of the spacing means when the side flaps are in their upright positions.

4. A bottle carrier comprising an elongated strip of flexible material creased transversely forming a bottom panel adapted to support two rows of bottles extending side by side transversely of the strip and two side panels adapted to fold upwardly along said crease lines, the end portions of the side panels having registering openings and constituting the handle portion of the carrier, means for spacing the bottles apart and for holding them in position on the bottom panel comprising a spacing strip of approximately the same dimensions as the bottom panel and having openings through which the lower parts of the bottles may extend and flaps hinged to the ends of the bottom panel and the spacing strip and adapted to support the latter strip above the

bottom panel, the side panels each having an opening in its upper part, below the handle portion, through which the bottles composing a row may be inserted into or removed from the carrier, and interlocking devices between said spacing means and said side panels for preventing endwise movement of the spacing means when the side panels are in their upright positions.

5. A bottle carrier comprising an elongated strip of flexible material creased transversely forming a bottom panel adapted to support two rows of bottles extending side by side transversely of the strip and two side panels adapted to fold upwardly along said crease lines, the end portions of the side panels having registering openings and constituting the handle portion of the carrier, means for spacing the bottles apart and for holding them in position on the bottom panel comprising a spacing strip of approximately the same dimensions as the bottom panel and having openings through which the lower parts 20 of the bottles may extend and flaps hinged to the ends of the bottom panel and the spacing strip and adapted to support the latter strip above 25 the bottom panel, each side panel having a cut extending downwardly from the handle portion near one of the side edges of the panel, thence transversely of the panel and thence upwardly to the handle portion near the opposite edge of the panel, forming an opening through which the bottles composing a row may be inserted into

the carrier and forming a tongue depending from the handle portion adapted to extend between the rows of bottles, and interlocking devices between said spacing means and said side panels for preventing endwise movement of the spacing means when the side panels are in their upright positions.

6. A bottle carrier comprising an elongated strip of flexible material creased transversely forming a bottom panel adapted to support two rows of bottles extending side by side transversely of the strip and two side panels adapted to fold upwardly along said crease lines, the end portions of the side panels having registering openings and constituting the handle portion of the carrier, means for spacing the bottles apart and for holding them in position on the bottom panel comprising a spacing strip of approximately the same dimensions as the bottom panel and having openings through which the lower parts 20 of the bottles may extend and flaps hinged to the ends of the bottom panel and the spacing strip and adapted to support the latter strip above the bottom panel, the handle portions having hand openings which register when the carrier is set up, the opening in one portion being shorter than the opening in the other portion, and a tongue formed in the larger opening and having shoulders adapted to interlock with the edges of the smaller opening.
